[57] CLAIM

The ornamental design for the emergency position indicating radio beacon, as shown and described.

DESCRIPTION

FIG. 1 is a left side elevational view of an emergency position indicating radio beacon showing our new design, with the antenna broken away to indicate indeterminate length;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof; and,

FIG. 7 is a perspective view taken from the top, front, and left side of the emergency position indicating radio beacon.
